US00D585763S

(12) **United States Design Patent**
Friebe et al.

(10) **Patent No.:** **US D585,763 S**
(45) **Date of Patent:** **** Feb. 3, 2009**

(54) **FOIL PACKAGE**

(75) Inventors: **Joachim Friebe**, Heimertingen (DE);
Andreas Michalsky, Memmingen (DE);
Maurice Habram, Kempten (DE);
Agata Surdziel, Kempten (DE); **Peter Ganz**, Untrasried (DE)

(73) Assignee: **Huhtamaki Ronsberg, Zweigniederlassung der Huhtamaki Deutschland GmbH & Co. KG** (DE)

(**) Term: **14 Years**

(21) Appl. No.: **29/299,498**

(22) Filed: **Dec. 27, 2007**
